STANLEY R. HOWARD, OF EAST MILTON, MASSACHUSETTS, ASSIGNOR TO PNEUMATIC SCALE CORPORATION, LIMITED, OF QUINCY, MASSACHUSETTS, A CORPORATION OF MASSACHUSETTS.

DRIVING MECHANISM.

Application filed January 5, 1927. Serial No. 159,099.

This invention relates to a driving mechanism for a rotary member.

The invention has for an object to provide a novel and improved mechanism for driving a rotary member, which is particularly adapted for use in driving the rotary spider of the wrapping machine of my copending application Serial No. 159,100, filed January 5, 1927, but which in addition may be used 10 with advantage in other machines whose operation involves an intermittent revolution of an element combined with an independent rotation of the element.

With this object in view and such others 15 as may hereinafter appear, the invention consists in the driving mechanism, and in the combinations hereinafter described and particularly defined in the claims at the end of this specification.

20 The drawings illustrate the invention as embodied in a driving mechanism for causing the spider of a box banding machine to be intermittently revolved and successive of the box holding blocks to be rotated at 25 the banding station, and wherein Figure 1 is a front elevation of a driving mechanism embodying the present invention; Fig. 2 is a detail in section through the spider; and Fig. 3 is a vertical longitudinal section 30 through the same.

Referring to the drawings, different features of the present driving mechanism are, as above stated, shown as embodied in mechanism for driving the spider of a box banding machine, and the latter comprises the machine forming the subject matter of my copending application. A sufficient portion of such box banding machine has been herein shown to illustrate the present driving 35 mechanism, and briefly such machine is provided with a rotatable spider provided at its forward end with four blocks spaced 90 degrees apart upon which the boxes are carried during the banding operation. Provision is made for intermittently rotating 40 the spider, step by step, 90 degrees at a time, so as to present each of these blocks successively to a receiving station, where a box to be banded is placed upon the spider, 45 then to a banding station where a strip of banding paper previously coated with an adhesive is wrapped completely about the sides and ends of the box so that it overhangs the 50 top and bottom edges of the same, then to a

folding station where these overhanging portions are folded over upon the bottom of the box and over the top edges thereof and then to a pressing and delivery station at which the previously banded box, upon its block, is pushed through a set of yielding 60 presser rolls which act to more firmly fix the wrapper to the box. The box is delivered onto a table or shelf, being retained upon this shelf by suitable strippers as the block retracts, and thereafter being pushed 65 onto a constantly driven discharge conveyor placed adjacent said shelf by the next box delivered upon the shelf.

The present driving mechanism functions 70 to impart the intermittent revolution to the spider and the independent rotation of the successive blocks at the banding station. The spider, herein shown at 12, is pivotally mounted on the forward end of a shaft 14 which is journalled at 16 and 18 in bearings secured to the frame of the machine, and has rotatably and slidably mounted at intervals of 90 degrees on its periphery the 75 shafts 20, 22, 24 and 26 which carry on their forward ends the blocks 28, 30, 32 and 34, 80 respectively.

In these figures the block 28 is shown at the box receiving station of the banding machine, 30 at the banding station, 32 at the folding station, and 34 at the pressing 85 and delivery station.

For the purpose of intermittently rotating the spider to move each of these blocks successively through each of these stations, an arm 36 is secured to the rear end of the shaft 90 14. This arm is connected by a link 38 to the outer end of a crank arm 40 pivoted at 42 to the frame of the machine. The crank arm 40 is rocked by a block 44 pivotally mounted on a crank pin 46 secured to a gear 48. The length of the link 38 is adjustable and also the effective length of the arm 36, and these lengths may be adjusted so as to 95 rock the shaft 14 exactly 90 degrees each time the crank arm 40 is rocked. In order that the spider 12 may be rotated 90 degrees in a clockwise direction (as seen in Figs. 1 and 2) each time the shaft 14 is rocked in that direction, a latch arm 50 is secured to the shaft 14 within the spider 12 with its hub adjacent that of the spider. This latch arm has a radially disposed latch 52 mounted in a slide therein which is urged out-

wardly by a spring 54. This latch cooperates with successive of a series of four peripheral slots 56 in the spider 12 to connect the spider and latch arm 50 and to thereby rock the spider in a clockwise direction upon similar movement of the shaft 14 and the latch arm 50. In order to permit the latch arm 50 to be returned independently of the spider when counter-clockwise rotation of the shaft 14 takes place, provision is made for disengaging the latch 52 from the particular slot 56 in which it was received during the preceding forward part of oscillation of the shaft 14 and the spider, and in addition provision is also preferably made for locking the spider in the position into which it has been advanced by the forward oscillation of the latch arm 50. In the illustrated machine, as shown in detail in Fig. 2, a radially movable lock 58, located externally of the spider, is arranged to be inserted by mechanism to be described, into the particular slot 56 with which the latch 52 is engaged during the forward movement of the latch arm 50, disengaging the latch 52 from the spider and permitting the latch arm 50 to be free to rotate in a counter-clockwise direction with the shaft 14. At the same time, the lock 58 serves to prevent return movement of the spider in a counter-clockwise direction. During the counter-clockwise rotation of the latch arm 50, a roll 60 journaled in the outer end of the latch 52 rides upon the inner cylindrical surface 62 of the spider until the latch at the end of this movement comes into alignment with another of the slots 56 and is forced into it by the spring 54, the parts then being again in the position shown in Figs. 1 and 3. In order that the lock 58 may be inserted at the proper time into one of the slots in the spider 12 to lock the latter against counter-clockwise rotation and later withdrawn at the proper time to permit clockwise rotation of the spider, the lock 58 is mounted in slide-ways 64 formed in a bracket 66 secured to the frame of the machine and is moved therein by means of an arm 68 secured to a rock shaft 70 journaled in the bracket 66 and another fixed bracket 72 and connected to the lock 58 by a pivoted block 74. The shaft 70 is rocked by an arm 76 secured to its rear end and connected by a link 78 to the outer end of a cam arm 80 mounted on a stud 82 secured to a bracket 84 secured to the frame of the machine. The cam arm 80 carries a cam roll 86 which cooperates with a suitably shaped cam groove in a cam 88 secured to a constantly rotating shaft 90 to impart the desired timed movement to the lock 58 through the connections described.

In the banding machine in which the present invention is shown as embodied a set up box to be banded is placed upon the particu-

lar block at the receiving station, and thereafter the block with the box thereon is advanced in the manner and by the mechanism just described. The banding station is illustrated by the position occupied by the block 70 30 in Fig. 1, and after the particular block bearing the box to be banded arrives at the banding station, provision is made in the illustrated machine for rotating the block through one revolution, and while the block 75 is thus revolved provision is made by mechanism not shown for holding an adhesive banding strip against the lateral surface of the box thereon to thereby wrap the banding strip around the box. 80

The mechanism for selectively rotating each of the blocks 28, 30, 32 and 34, after it has arrived at the banding station in order that the wrapper may be wrapped about the box may be described in detail as follows: 85

The shafts 20, 22, 24 and 26 upon which the blocks are mounted have splined to them sleeves 92, 94, 96 and 98, respectively, having formed on their rear ends gears 100, 102, 104 and 106. A segmental gear 108 which meshes with these gears 100, 102, 104 and 106, while at the banding station, is rotatably mounted on a fixed bearing 110, eccentric with respect to the shaft 14, and formed on the forward end of a conical shell 112 90 (see Fig. 3) secured to the frame. 95

The shell 112 also carries the bearing 16 for the shaft 14. The segmental gear 108 has secured to the outer portion of its front face a bracket 113 which carries a roll 114 100 which engages the sides of a radial slot 115 formed in the periphery of the latch arm 50, thus connecting the latch arm 50 and the segmental gear 108 in such a manner that when the latch arm is rotated 90 degrees in either direction with the rock shaft 14 the segment 108 is rotated slightly more than 90 degrees in the same direction upon its eccentric bearing 110. It may be seen from an inspection of Figs. 1 and 2 that the eccentricity of the bearing 110 with respect to the shaft 14 is in such a direction as to cause the teeth of the segment 108 to mesh with any one of the gears 100, 102, 104 or 106 located at the banding station and prevents engagement with any of them at any of the other three stations. During the clockwise rotation of the spider 12, the latch arm 50 and segment 108 will be moved from the position shown in Fig. 1 to that shown in 105 Fig. 2 and the block 30 will be moved from the banding station to the folding station. During this movement the teeth of the gear 102 will gradually move out of mesh with the teeth of the segment 108. At the same time the block 28 will be moved from the receiving station to the banding station, and the teeth of its gear 100, will be gradually brought into mesh with those of the segment 108 and will be wholly in mesh when 110

115 120 125 130

engagement with any of them at any of the other three stations. During the clockwise rotation of the spider 12, the latch arm 50 and segment 108 will be moved from the position shown in Fig. 1 to that shown in Fig. 2 and the block 30 will be moved from the banding station to the folding station. During this movement the teeth of the gear 102 will gradually move out of mesh with the teeth of the segment 108. At the same time the block 28 will be moved from the receiving station to the banding station, and the teeth of its gear 100, will be gradually brought into mesh with those of the segment 108 and will be wholly in mesh when 110 115 120 125 130

the parts reach the position shown in Fig. 2. During this movement neither of the gears 100 and 102 are rotated about their own axes 20 and 22. When, however, the 5 latch arm 50 and segment 108 rotate in a counter-clockwise direction and the spider is prevented from such rotation by the lock 58, the engagement of the teeth of the segment with those of the gear 100 will cause 10 the latter and the block 28 to be rotated in a clockwise direction. The pitch radii of the segment 108 and gear 100 are preferably so proportioned that this rotation of slightly more than 90 degrees of the segment 15 will rotate the gear and block exactly one revolution as is desired.

In order that the blocks 28, 30, 32 and 34 may be prevented from rotating at all times excepting while at the banding station, as 20 above described, the gears 100, 102, 104 and 106 have secured to them shoes 116, 118, 120 and 122 arranged to ride upon the periphery of a circular disk 124 secured to a flange 126 formed on the shell 112, the shoes having 25 concave faces 128 closely fitting this periphery. A recess 130 is formed in the disk 124 opposite the banding station of a size sufficient to permit the shoes 116, 118, 120 and 122 to rotate within the same. 30 While the present driving mechanism has been illustrated and described as embodied in mechanism for intermittently revolving the spider of a box banding machine, and for imparting independent rotation of the 35 box holding block while at the banding station, it is to be understood that the different features of the invention may be embodied in other machines within the scope of the following claims.

40 Having thus described the invention, what is claimed is:—

1. The combination with a supporting member, having an article holding device rotatably mounted therein, of mechanism 45 for intermittently revolving the supporting member and for rotating the article holding device, including an oscillatory element, connections between the oscillatory element and supporting member, and connection between the oscillatory element and the article holding device.
  2. The combination with a supporting member, having an article holding device rotatably mounted therein, of a rotary actuating element, connections between said rotary element and the supporting member for intermittently revolving the latter, and connections between said rotary element and the article holding device for rotating the 55 article holding device with relation to the supporting member.
  3. The combination with a supporting member, having an article holding device rotatably mounted therein, of a rotary actuating element, connections between said 60
- rotary element and the supporting member for intermittently revolving the latter, connections between said rotary element and the article holding device for rotating the article holding device with relation to the 70 supporting member, and means for preventing revolution of said supporting member when the article holding device is rotated.
4. The combination with a supporting member, having an article holding device 75 rotatably mounted therein, of mechanism for intermittently revolving the supporting member, and for rotating the article holding device, including an oscillating element, and means having provision whereby the 80 supporting member is advanced when said element oscillates in one direction, and the article holding device is rotated when said element oscillates in the reverse direction.
5. The combination with a supporting 85 member provided with a plurality of article holding devices rotatably mounted therein and each provided with a gear, means for intermittently revolving said supporting member through a plurality of stations, and means for rotating successive of the article holding devices with relation to the supporting member while at a particular station, including an operating gear normally disengaged from said gears of the article holding devices, means for causing the operating gear to mesh with a particular one of the article holding device gears during movement of the latter into a particular station, and for permitting said gear to be rotated 90 by said operating gear during the return oscillation of the latter.
6. The combination with a supporting member having a plurality of article holding devices rotatably mounted therein, and 95 each provided with a gear, of means for intermittently revolving said supporting member, including an oscillatory latch arm, a latch mounted thereon and adapted to cooperate with said supporting member, means 100 for controlling the operation of the latch whereby the supporting member is advanced when the latch arm advances and is prevented from movement during the return oscillation of said latch arm, and means for 105 rotating an article holding device gear with relation to said supporting member, including an operating gear connected to move with said latch arm, means for causing the operating gear to mesh with the article holding device gear without causing rotation of the latter during the revolution of the article holding device and supporting member into a particular station whereby 110 said gear may be rotated by said operating gear during the return oscillation of said latch arm.
- In testimony whereof I have signed my name to this specification.

STANLEY R. HOWARD.
